UNITED STATES PATENT OFFICE.

THOMAS HENRY WHITE, OF PENDLETON, SALFORD, ENGLAND.

HOT-WATER INJECTOR.

1,082,220.

Specification of Letters Patent. Patented Dec. 23, 1913.

Application filed October 21, 1912. Serial No. 727,019.

To all whom it may concern:

Be it known that I, THOMAS HENRY WHITE, a subject of the King of Great Britain and Ireland, and resident of Pendleton, Salford, in the county of Lancaster, England, have invented certain new and useful Improvements in Hot-Water Injectors, of which the following is a specification.

This invention has reference to improvements in injectors for hot water, and has for its object to render the starting or re-starting of such injectors absolutely certain and reliable.

It is usual in injectors of the kind referred to and also in certain other kinds to provide overflow or escape valves, which may be either open, or are selffactingly opened at starting or re-starting of the injector and allow the escape of steam or fluid from an orifice or gap or orifices or gaps as the case may be, situated either upon or between the nozzles, and also allowing in certain cases, the escape of steam or fluid from certain other points upon such nozzles, the valves closing selffactingly when the jet has been established in such a manner as to prevent egress or escape of such jet to the atmosphere.

Referring to the 2 sheets of drawings hereto appended four different kinds of injectors are shown as examples of the manner in which the invention may be carried out, which are of single tube type, but I desire it to be distinctly understood that the arrangements of self-acting valves as shown, may be applied to any other type of injector, to which they may be suitable or adaptable.

In Figure 1 the valves are shown arranged to close by the medium of steam pressure, but they may alternatively by suitable arrangement of a passage to the delivery chamber, in lieu of that to the steam chamber of the injector be equally well arranged to close the agency of boiler pressure. In Fig. 2 the valves are shown, arranged to close by the medium of boiler pressure, but they may alternatively by a suitable arrangement of a passage to the steam chamber in lieu of that to the delivery chamber of the injectors, be equally well arranged to close by the agency of steam pressure. Fig. 3 shows an example of closing the valves by boiler pressure, and Fig. 4 illustrates a similar example of closing the valves by overflow pressure only.

The arrangement of and manner in which the said self-acting valves operate, as shown by the various drawings may be described as follows:

In the injector shown by Fig. 1, steam being admitted at starting, flows through the cones 1, 1^a, 2, 3, 3^a, and passes by way of the gaps 4, 5 and 5^a into chambers 6 and 7 which are controlled respectively by the valves 8 and 9. Immediately the steam sets up pressure in such chambers 6 and 7 the valves 8 and 9 are moved from their seats thereby and the steam escapes to the atmosphere by way of the annular passage 10 and overflow outlet 11. A small relief valve 12 having movement within the guide on cap 12^a and a piston 13 having movement within the guide 13^a are arranged as shown on the same axial lines respectively as the valves 8 and 9 are. The valve 12 is nearly in contact with the valve 8 while the piston impinges upon valve 9. It will be obvious therefore that as the valves 8 and 9 are blown outward by the steam, they will by impingement, also move the valve 12 and piston 13 outward. Now the valve 12 in this position is open and so allows any steam passing from the steam chamber 1^b by way of the passage 14 into the chamber 15 to freely escape through the orifice upon which the valve 12 seats itself, into the annular passage 10 and thence to the atmosphere by the overflow outlet 11 and in consequence of this the valves 8 and 9 at starting of injector, have full and unimpeded movement. When the jet has been formed steam pressure will not exist in the chamber 6 and the valve 8 therefore returns to its seat by gravity. Steam passing from chamber 1^b by passage 14 enters chamber 15 and acting upon the upper side of valve 12 positively closes it to its seat. The steam further passes through the passage 16 into the chamber 17, acts upon the piston 13 and causes it to also close the valve 9 to its seat. Thus, as is necessary when the injector is in operation, all outlets for the escape of fluid from any one chamber into any other chamber, or from any chamber to the atmosphere, are suitably closed. In event of the action of the injector being interrupted steam again passes into the chambers 6 and 7 and the whole process in relation to the action of the valves as hereinbefore described is repeated. A supplementary water inlet valve is shown by 18 to admit a secondary

supply of water to the injector cones, when necessary. In this arrangement it will be noted, that the chambers 6 and 7 are separate and distinct.

- 5 In the injector as shown by Fig. 2, steam being admitted at starting flows through the cones 1, 2, 3, and passes by way of the gaps 4 and 5 into chambers 6 and 7 which are controlled respectively by the valves 8 and 9. Immediately the steam sets up pressure in the chambers 6 and 7, the valves 8 and 9 are moved from their seats thereby. The steam in chamber 6 passes through the orifice upon which the valve 8 seats itself, 10 enters chamber 7 and flows with the steam therein past the valve 9 into passage 10 and thence by way of the overflow outlet 11 to the atmosphere. A small relief valve 12 having movement in the guide 12^a and a piston 13 having movement fluid tight in the guide 13^a are arranged as shown on the same axial lines respectively as the valves 8 and 9. The valve 12 is nearly in contact with the valve 8 while the piston 13 impinges upon 9. It will be obvious therefore, 15 that as the valves 8 and 9 are blown outward by the steam that they will, by impingement, also move the valve 12 and piston 13 outward. Now the valve 12 in this position is open and so allows any steam passing into chamber 15 by way of the delivery tube 19, chamber 20 and passage 14 to freely escape through the orifice upon which the valve 12 seats itself, thence between the webs on valve 8 into the chamber 20 and by the valve 9 and passage 10 to the overflow outlet 11, and in consequence of this, the valves 8 and 9 at starting of the injector have full and unimpeded movement. 25
- 30 When the jet has been formed, the valves 8 and 9 fall to their seats by gravity, while fluid on its emergence from the tube 19, flows by way of 20 and passage 14, into chamber 15, forming fluid pressure therein, 35 which acting upon upper side of relief valve 12 firmly retains it on its seating. Now as will be seen from the drawing and as hereinbefore stated there is a slight amount of play or clearance between the valves 8 and 12 and as there will be a certain flow of fluid from the chamber 6, due to escape from the gap 4, the valve 8 in consequence would not hold fluid tight upon its seat as is necessary, were it not for the fact that 40 there is a greater volume of fluid escaping from the gap 5 into chamber 7, and this rapidly forming pressure in the said chamber 7, acts upon the upper side of the valve 8, and consequently retains it upon its seat. 45
- 50 Thus, as is necessary, when the injector is in operation all outlets for the escape of fluid from any one chamber into any other chamber, or from any chamber to the atmosphere are suitably closed. In event of the injector 55 being interrupted, steam again passes into

the chambers 6 and 7, and the whole process in relation to the action of the valves, as hereinbefore described, is repeated. It will be noted that unlike the arrangement shown in Fig. 1, in this modification, the chambers 6 and 7 are in communication one with the other, by means of the orifice controlled by valve 8. In this Fig. 2 an unloaded non-return valve in the suction branch of the injector intended as hereinbefore described to prevent any back flow of steam into the water suction pipe, and to render the action of the above overflow valves more positive and certain, is shown by 21.

55 In Fig. 3, a further arrangement of these self-acting valves in a single tube injector is shown. The arrangement and operation of such being as follows:—On starting of injector, steam flows through cones 1, 2, 3, and passes by gaps 4, 5, into the chamber 6, and opening the valve 8 passes to the atmosphere by way of the overflow outlet 11. On the same axis as the valve 8 are the pistons 22 and small relief valve 12, the piston sliding fluid tight through the valve, which is suitably bored to receive it, while the valve, which is of ordinary webbed or winged form, so as to allow the passage of fluid between such webs or wings, slides within suitable orifice prepared to receive it 60 in the guide 23. The valve 12 is nearly in contact with the valve 8 while the piston 22 impinges upon 8. Obviously therefore as valve 8 is blown from its seating it will also move the piston 22 and valve 12. In this 65 position the valve 12 is open and thus allows any steam passing into chamber 20 by way of the delivery tube 19 to freely escape through the orifice upon which valve 12 seats itself, thence by 11 to the atmosphere, 70 and in consequence of this at the starting of the injector the valve 8 has full and unimpeded movement. When the jet is established, fluid emerging from the delivery tube 19 closes the valve 12 to its seat, and in consequence fluid pressure accumulates in the chamber 20 and returns the valve 8 by means of the piston 22 to its seat and effectually seals the chamber 6. In event of the action 75 of the injector being interrupted, steam again passes into chamber, and the whole process in relation to the action of the valves is repeated. A sleeve valve 24 arranged and operating in the known way is shown on the cone 3 for closing the gap 4 and preventing 80 entry of fluid from the gap 4 into 6.

85 In the modification shown by Fig. 4, the arrangement of the self-acting valves is somewhat similar to that shown by Fig. 3, but in Fig. 4, the valves are closed by overflow pressure and not as in Fig. 3 by boiler pressure. The arrangement and operation of the valves in Fig. 4 is as follows:—On starting of the injectors, steam flows through cones 1, 2, 3, and passes by gaps 4, 5, into 90

chambers 6 and 7 and opening valve 8, flows by way of the passage 10 and overflow outlet 11, to the atmosphere. On the same axis as valve 8 is the piston 22 and small relief valves 12, which are arranged and act on starting the injector, as described with reference to the parts indicated by the same letters in Fig. 3, so that the valve 12 is open and thus allows any steam passing into chamber 7 by the gap 5 to escape freely through 10 and 11 to the atmosphere, and so the valve 8 has free and unimpeded movement. When the jet is established, fluid emerges from the gap 5, closes the valve 12 and the fluid pressure accumulating in the chamber 7 closes the valve 8 by means of the piston 22, and the chambers 6 and 7 are effectually sealed, and as is necessary when the injector is in operation, all outlets for the escape of fluid from any chamber to the atmosphere are closed. In event of the action of the injector being interrupted steam again passes into chambers 6 and 7 and the whole process in regard to the action of the valves is repeated.

It will be noted that only in Fig. 1 is a supplementary water inlet valve shown, but such fitting may be equally applied to the other injectors as shown by the Figs. 2, 3, 30 and 4. Likewise, the non-return valve 21 in the suction branch, is only shown in Fig. 2, but it may equally well be applied to the injectors as shown by Figs. 1, 3, and 4.

I claim as my invention.

35 1. In injectors for hot water the combination of nozzles having gaps between them, chambers surrounding said nozzles and gaps and provided with outlet orifices, an overflow passage communicating with said orifices and leading to the overflow outlets, free lifting or moving overflow valves adapted to close said orifices, a chamber filled with steam or water or both at the starting or restarting of the injector, a small orifice 40 therein leading into said overflow passage, a free lifting or moving valve closing said small orifice and adapted to be opened by the outward movement of one of the overflow valves.

50 2. In injectors for hot water the combina-

tion of nozzles having gaps between them, chambers surrounding said nozzles and gaps and provided with outlet orifices, an overflow passage communicating with said orifices and leading to the overflow outlet, free 55 lifting or moving overflow valves adapted to close said orifices, a chamber filled with steam or water or both at the starting or restarting of the injector, a small orifice therein leading into the said overflow passage and arranged coaxially with one of said overflow valves, and a free lifting or moving valve closing said small orifice and nearly in contact with the overflow valve.

3. In injectors for hot water the combination of nozzles having a gap between them, a chamber surrounding said gap and provided with an outlet orifice, an overflow passage communicating with said orifice and leading to the overflow outlet, a free lifting 65 or moving overflow valve adapted to close said orifice, a chamber filled with steam or water or both at starting or restarting of the injector, a small orifice therein leading into said overflow passage, a free lifting or moving valve closing said orifice and adapted to be opened by the outward movement of said overflow valve.

4. In injectors for hot water the combination of nozzles having a gap between them, 80 a chamber surrounding said gap and provided with an outlet orifice, an overflow passage communicating with said orifice and leading to the overflow outlet, a free lifting or moving overflow valve, adapted to close 85 said orifice, a chamber filled with steam or water or both at starting or restarting of the injector, a small orifice therein leading into said overflow passage and arranged coaxially with said overflow valve, and a free 90 lifting or moving valve closing said small orifice and nearly in contact with the overflow valve.

In testimony whereof I have hereunto affixed my signature in the presence of two 95 witnesses.

THOMAS HENRY WHITE.
